UNITED STATES PATENT OFFICE.

GEORGE W. COPE, OF DETROIT, MICHIGAN, ASSIGNOR TO THE ART STOVE COMPANY, OF SAME PLACE.

DESIGN FOR AN OIL HEATING-STOVE.

SPECIFICATION forming part of Design No. 23,090, dated February 27, 1894.

Application filed December 19, 1892. Serial No. 455,700. Term of patent 7 years.

To all whom it may concern:

Be it known that I, GEORGE W. COPE, a citizen of the United States, residing at Detroit, county of Wayne, State of Michigan, have invented and produced a certain new and original Design for an Oil Heating-Stove; and I declare the following to be a full, clear, and exact description of the invention, such as will enable others skilled in the art to which it appertains to make and use the same, reference being had to the accompanying drawing, which forms a part of this specification.

The drawing submitted herewith is a perspective view of an oil stove, showing my design.

The drawing shows the front and one side of the stove, the two sides, it will be understood, being essentially alike, as also the front and rear.

I carry out my invention as follows:

A, denotes an ornamental square leg frame, provided with legs; "a." Said leg frame is ornamented with scroll work, as shown.

B, denotes a square tank chamber, which I construct with a plain exterior surface.

C, denotes the walls of the combustion or burning chamber, constructed with a cover portion C', extending over the wall of the tank chamber and having rounded corners. This cover portion C', is also ornamented with scroll work, as shown. At the four corners of the combustion or burning chamber, are vertically extended flue tubes, C². The outer surface of each flue tube is rounded in horizontal cross-section, and is also curved vertically with a substantial cyma-curve, and terminates in a knob or boss, surmounted by an ornamental representation of an open flower shown at "c." Resting on the upper ends of said flue tubes is an annular chamber D, the wall of which is oval in vertical cross-section.

On each side of the stove between the two adjacent ornamented flue tubes C² is an inwardly projecting or deeply-seated light open-

ing E. From the extreme outer edges of the flues to the inner edges thereof adjacent to the said light openings, the walls of the flue tubes are ornamented with scroll work, as indicated in the drawing. The annular chamber D, from its extreme outer edge to its inner edge adjacent to the light openings is also ornamented with scroll work.

F, is a cylindrical heating drum or chamber, smooth on its exterior with the exception of corrugations between the top and bottom thereof as shown at f, f'.

G, is a dome-shaped top located upon the annular chamber F, ornamented with scroll work, and supporting an urn G'. Beneath the dome-shaped top is an annular projecting collar H, constructed with ornamentally shaped holes or orifices therein. The dome is also constructed with ornamentally shaped holes or orifices therethrough.

The more important features of my design, as will thus be seen, consist in the square ornamental base, the inwardly projecting or deeply-seated light openings in the burner chamber, the cylindrical drum, and the ornamental top.

What I claim as my invention is—

The design for an oil heating-stove consisting of an ornamented square leg-frame, a square tank chamber, a burning-chamber having deeply-seated light-openings, the side and bottom approaches to said openings being ornamented with scroll work, the meeting edges of contiguous openings being rounded and finished vertically in a cyma-curve terminating at its upper end with an open flower, a round heating chamber, and a dome-shaped top, substantially as shown and described.

In testimony whereof I sign this specification in the presence of two witnesses.

GEORGE W. COPE.
